J. H. VINEBERG ET AL.

WINDSHIELD ATTACHMENT

Filed Feb. 8, 1921.

UNITED STATES PATENT OFFICE.

JOSEPH HIRSCH VINEBERG AND JOSEPH PRESNER, OF MONTREAL, QUEBEC, CANADA.

WINDSHIELD ATTACHMENT.

Application filed February 8, 1921. Serial No. 443,466.

To all whom it may concern:

Be it known that we, JOSEPH H. VINEBERG, and JOSEPH PRESNER, of the city of Montreal, Province of Quebec, Dominion of Canada, both subjects of the King of Great Britain, have invented certain new and useful Improvements in Windshield Attachments; and we do hereby declare that the following is a full, clear, and exact description thereof.

10 Our invention relates particularly to attachments for protecting the eyes of the occupants of the front seat of an automobile from the sun's rays and sheltering the windshield glass from rain and sun for the purpose of reducing to a minimum the danger of the chauffeur's vision being interfered with by rain or sun obscuring the glass. The invention has for its object to provide a protector of this type which is readily operated and 20 is simple and inexpensive to manufacture while being adapted for use in connection with any form of wind shield or other glazed frame subjected to the elements.

To this end the invention consists of a carrier for a roller blind, means for extending the blind automatically and manually operated means for withdrawing the same from extended position. In the preferred embodiment of our invention a pair of spring 30 actuated arms project the blind to extended position by acting upon the forward edge thereof and a cord, tape or strap secured to the blind co-operating with a spring roller upon which the blind is carried enables the 35 chauffeur to withdraw the blind.

For full comprehension, however, of our invention reference must be had to the accompanying drawings in which similar reference characters indicate the same parts, and 40 wherein:

Figure 1 is a plan view of the underside of our improved wind-shield attachment;

Figure 2 is a similar view thereto drawn to a larger scale;

45 Figure 3 is a detail fragmentary view illustrating one end of the attachment;

Figure 4 is a similar view to Figure 3 illustrating the parts in section;

Figure 5 is a sectional view taken on line 50 5-5 Figure 2;

Figure 6 is a detail fragmentary end elevation illustrating the hinged connection between one of the blind-projecting arms and the end of the attachment;

Figure 7 is a detail view illustrating one 55 of the ends of the casing in which the roller for the blind is journalled;

Figure 8 is a sectional view taken on line 8-8 Figure 2;

Figure 9 is a sectional view taken on line 60 9-9 Figure 2; and

Figure 10 is an end elevation of the attachment drawn to a comparatively large scale.

The accompanying drawings illustrate the 65 preferred embodiment of our invention. This embodiment consists of a tubular casing or carrier 2 having a slot 3 extending throughout its length to permit the passage therethrough of the blind indicated at 4. 70 This blind is mounted upon a spring roller 5 provided at its ends with trunnions 6 which are journalled in sockets in inwardly-projecting hubs 7. The hubs are formed integrally with plugs 8 closing the opposite ends 75 of the casing, screws 9 rigidly securing the plugs in position.

The means for extending the blind consists of blind-projecting arms 10 located one at each end of the blind. These arms are constructed alike in all respects each being hinged at its outer end as at 12 upon a bracket 13 adjustably mounted on the adjacent plug 8. This adjustable mounting is obtained by a screw 14 which extends 85 through a central opening 15 in the bracket and is screwed into the plug. To adjust the angle of inclination of the blind, the screws 14 are loosened and the brackets turned thereon to the desired position after 90 which the screws are again tightened. The opposite end of each of the arms 10 is curved as at 17 and such curved ends are slotted as at 18.

Through these slotted ends studs 19 upon 95 a metal reinforcing strip 20 constituting the front edge of the blind, project. This reinforcing strip is preferably constructed in two parts adapted to clamp between them the edge of the blind, the parts presenting a 100 longitudinal channel 21 accommodating a wire 22 sewn into the blind. The parts are secured together by rivets or the like as at 23. The outer end of each arm adjacent its point of fulcrum is provided with a tail 24 105 having an opening or eye 25 therein and these two tails are connected together by a resilient device including a pair of helical

springs 26 and 27. These springs are of sufficient strength to overcome the torque of the spring of the roller so that the former will yieldingly maintain the arms in their projected positions.

The means we prefer to use in order to withdraw the blind from projected position consists of a leather strap or tape 16 one end of which is secured as at 28 to the underside of the reinforcing strip the opposite end being provided with a loop 29 constituting a hand-hole. This strap or tape is passed through an opening 30 in an arm 31 such arm being mounted upon the casing 15 midway the length thereof the strap having slits 33 cut therein to receive the stud.

To secure the inner end of the blind upon the spring roller in such a manner that it will not become readily displaced therefrom, the roller is provided with a peripheral groove 34 extending throughout the length thereof and the blind is secured within this groove by a rod or wire 35. The latter is sewn into the blind and is retained 25 in position in the groove by rings 36 located at the ends of the roller and by split collars 37 encircling the roller intermediate the rings and uniformly spaced apart.

The means for mounting our improved attachment upon the wind-shield consists of 30 an angular bracket 38 formed integrally with each of the plugs 8, the outer end of the bracket being disposed parallel to the length of the casing and having a slot 39 therein. The slot accommodates the shank 35 of a clamp screw 40 screwed into an arm 41 this arm having a fixed jaw 42 adapted to coact with a movable jaw 43 in gripping the vertical rail 44 of the wind-shield. The 40 movable jaw is adjustably mounted upon the arm by a screw 45 and it is provided with a tail 46 having a screw-threaded opening therethrough indicated at 47 such opening accommodating a locking screw 48. 45 The purpose of this locking screw is to cause the movable jaw to bind when the screw 45 is tightened.

It is to be distinctly understood that our improved wind-shield attachment may be 50 clamped upon the top of the wind-shield instead of upon the vertical posts thereof, or it may be permanently secured to a vehicle having a fixed top such as a limousine with slight alterations, without departing from 55 the spirit of the invention.

From the foregoing it will be seen that in order to shield the eyes of the driver from the sun or protect the glass from rain or sun it is only necessary for the tape 16 to be released and the arms 10 will automatically project the blind to its full outward position.

Although we have shown a tape fastened to the front edge of the blind this may be dispensed with and a pulley mounted upon

the roller and a cord or tape wound around the same, without departing from the spirit of our invention.

What we claim is as follows:

1. A storm and sun shield comprising a 70 roller, a blind wound upon the roller, lever arms one end of each being pivoted at the ends of the roller and having their opposite ends in operative engagement with the forward end of the blind said arms being 75 adapted to assume positions parallel to the roller when the blind is withdrawn and to extend parallel to the plane of the blind and beneath the same when the blind is extended, resilient means operatively connecting the lever arms together to maintain the same yieldingly in extended position, and manually operated means for withdrawing the blind.

2. A storm and sun shield comprising a 85 spring roller, a blind wound upon the roller, lever arms pivoted at one end at opposite ends of the roller and having their free ends in operative engagement with the forward edge of the blind, the pivoted ends of these 90 lever-arms having tails of hook form, springs operatively connecting the hooked tails together to maintain the arms and the blind in extended position, and manually operated means for withdrawing the blind. 95

3. A storm and sun shield comprising a tubular casing having a longitudinal slot therein a spring roller journalled within the casing, a blind wound upon said roller and adapted to be extended through said slot, a reinforced member upon the forward end of said blind, means for automatically extending said blind through the slot, said means consisting of a pair of lever arms one end of each arm being fulcrumed upon 100 said casing and the other end of said arm being slotted, studs upon said reinforcement member and in operative engagement with said slotted ends, and springs connected to said arms and adapted to yieldingly maintain the latter and blind in extended position. 105

4. A storm and sun shield comprising a carrier, a roller journalled therein and having a groove in its periphery extending 115 throughout the length of same, a blind wound upon the roller and having one end secured thereto within said groove, means for securing the blind in said groove said means consisting of a rod lying in said 120 groove and a plurality of annular devices encircling said roller and preventing displacement of the rod, a plurality of lever arms one end of each of which is pivoted upon said carrier and the other end connected to the forward end of the blind, and resilient means operatively connecting the lever arms together to maintain the same yieldingly in extended position. 125

5. A storm and sun shield comprising a 130

- carrier, a roller journalled therein and having a groove in its periphery extending throughout the length of same, a blind wound upon the roller and having one end secured thereto within said groove, means for securing the blind in said groove said means consisting of a rod lying in said groove and a plurality of annular devices encircling said roller and preventing displacement of the rod, a plurality of lever arms one end of each of which is pivoted upon said carrier and the other end connected to the forward end of the blind, resilient means operatively connecting the lever arms together to maintain the same yieldingly in extended position, and manually operated means for withdrawing the blind.
6. A storm and sun shield comprising a carrier, a roller journalled therein and having a groove in its periphery extending throughout the length of same, a blind wound upon the roller and having one end secured thereto within said groove, means for securing the blind in said groove said means consisting of a rod lying in said groove and a plurality of annular devices encircling said roller and preventing displacement of the rod, a plurality of lever arms one end of each of which is pivoted upon said carrier and the other end connected to the forward end of the blind, resilient means operatively connecting the lever arms together to maintain the same yieldingly in extended position, and manually operated means for withdrawing the blind said last mentioned means consisting of a fixed member upon said carrier and a tension device secured to the forward end of the blind and adapted to be detachably fastened to said member.
7. A storm and sun shield comprising a tubular casing having a longitudinal slot therein, a roller journalled within said casing, a blind upon said roller and adapted to be extended through said slot, means for automatically extending the blind through the slot said means consisting of a pair of lever arms pivoted at opposite ends of the
- casing and operatively connected to said blind, and resilient means operatively connecting the lever arms together to maintain the same yieldingly in extended position, means for adjusting the angle of inclination of the blind when in extended position said means consisting of brackets adjustably mounted upon opposite ends of the casing each bracket pivotally carrying one of said arms and means for maintaining each of said brackets in adjusted position.
8. The combination with a fixed member; of a storm shield comprising a tubular casing having a longitudinal slot therein, a spring roller journalled in said casing, a blind upon said roller and adapted to be extended through said slot, means for automatically extending the blind said means consisting of a pair of lever arms having their forward ends in operative engagement with the forward end of the blind, means hingedly connecting the opposite ends of each of said lever arms to the casing, said means consisting of a bracket hingedly carrying one of said lever arms and adjustably mounted upon said casing for the purpose of enabling the alteration of the angle of inclination of the blind when extended, resilient means operatively connecting the lever arms to maintain the same yieldingly in extended position and means for clamping said shield upon a fixed member, said means consisting of a fixed jaw mounted upon each end of said casing, a movable jaw carried by said fixed jaw and adapted to coact therewith in gripping said member, means for moving said movable jaw relatively to said fixed jaw, and means for automatically causing said movable jaw to bind as it is moved towards said fixed jaw.
- In testimony whereof we have signed our names to this specification in the presence of two witnesses.
